US0D1076353S

(12) **United States Design Patent** (10) **Patent No.:** **US D1,076,353 S**
(45) **Date of Patent:** **** May 27, 2025**

(54) **SHOE**

(71) Applicant: **Skechers U.S.A., Inc. II**, Manhattan Beach, CA (US)

(72) Inventor: **Jung Kim**, Gardena, CA (US)

(73) Assignee: **Skechers U.S.A., Inc. II**, Manhattan Beach, CA (US)

(**) Term: **15 Years**

(21) Appl. No.: **29/932,996**

(22) Filed: **Mar. 16, 2024**

(51) LOC (15) Cl. **02-04**

(52) U.S. Cl.

USPC **D2/908**; D2/902; D2/953

(58) **Field of Classification Search**

USPC D2/902-908, 910-912, 946-962, 969, D2/970, 972-978

(57) **CLAIM**

The ornamental design for a shoe as shown and described.

DESCRIPTION

FIG. 1 is a front perspective view of a shoe in accordance with my new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof; and,

FIG. 8 is a bottom perspective view thereof.

The broken lines and the white shaded out area surrounded by broken lines shown in the drawings depict portions of the shoe and form no part of the claim.

1 Claim, 8 Drawing Sheets
